UNITED STATES PATENT OFFICE.

CHARLES G. SUTTON, OF CHERRYVALE, KANSAS.

LEVEL ATTACHMENT.

1,109,024.

Specification of Letters Patent.

Patented Sept. 1, 1914.

Application filed June 27, 1913. Serial No. 776,143.

To all whom it may concern:

Be it known that I, CHARLES G. SUTTON, a citizen of the United States, residing at Cherryvale, in the county of Montgomery and State of Kansas, have invented certain new and useful Improvements in Level Attachments, of which the following is a specification, reference being had to the accompanying drawings.

10 This invention relates to new and useful improvements in attachments for levels and more particularly to a device for obtaining angles of various objects, the object of the invention being to provide a device of the 15 above character which can be quickly and readily applied to an ordinary wooden straight edge whereby the same may be used for obtaining angles of various objects.

Another object of the invention is the 20 provision of a device of the above character which will possess advantages in points of efficiency and durability, is inexpensive of manufacture and at the same time is simple in construction and operation.

25 With the above and other objects in view, this invention consists in the novel features of construction and the combination and arrangement of parts to be hereinafter more fully described, pointed out in the claims 30 and shown in the accompanying drawings, in which--

Figure 1 is a side elevation of a leveling attachment constructed in accordance with my invention; Fig. 2 is a similar view illustrating the level tube holder in its blank form; Fig. 3 is a transverse sectional view; Fig. 4 is an end elevation illustrating the same attached to a straight edge.

Referring more particularly to the drawings, 1 indicates an ordinary straight edge, to the side of which is secured my improved attachment which consists of an arcuate body member 2 connected at its ends by means of the transverse web 3. The body member 2 is provided at its ends and at its intermediate portion with the outwardly projecting perforated ears 4 through which are adapted to be inserted screws or nails to securely fasten the body to the side of the said straight edge. The body member 2 is substantially arcuate in shape and is provided upon one face thereof with the graduations 5 which may be arranged in any desirable manner.

55 Formed integral with the web 3 at its intermediate portion is a downwardly project-

ing ear 6 upon which is pivotally mounted the lower end of an indicator 7, the point of which is adapted to be arranged opposite the graduated face of the body. The body 60 of the indicator 7 is formed from a substantially rectangular piece of metal, as indicated at 8, which is slit inwardly at various places, as indicated at 9, forming upon each side of the indicator two sets of 65 tongues, one set being somewhat larger and longer than the other. The larger set of tongues are rolled upon themselves to form the tubular side members 10 in which is arranged the level tube 11. A second set of 70 tongues which are indicated by the numeral 12 are then bent inwardly toward each other and arranged transversely across the ends of the members 10 so as to securely retain the tube 11 within said members. It will 75 be readily apparent that by having the level tube carried by the indicator, the device may be used for either leveling various objects or may be used for obtaining various angles by the use of the indicator 7. 80

From the above description taken in connection with the accompanying drawings, it will be readily apparent that I have provided a simple and durable attachment for the well known construction of levels in use 85 at the present time whereby they may be used to obtain the angles of various objects. It will also be apparent that by having the perforated ears 4 formed integral therewith, the device may be quickly and readily attached to the straight edge or removed therefrom. It will be understood that my improved attachment may be constructed of any suitable light weight material such as 90 aluminum or the like and that it is extremely simple in construction and can be manufactured at a comparatively low cost. 95

While I have shown and described the preferred form of my invention, it will be obvious that various changes in the details 100 of construction and in the proportions may be resorted to for successfully carrying my invention into practice without sacrificing any of the novel features or departing from the scope of the appended claims. 105

What I claim is:—

1. A device of the class described including an indicator formed of a single piece of material having slits formed therein to provide two sets of tongues, one set of tongues 110 being larger than the other and bent upon themselves to form tubular members and the

other set of tongues being bent inwardly and arranged across the ends of the tubular members, as and for the purpose set forth.

2. A device of the class described including an arcuate graduated body member, means for securing the same to a straight edge or the like, a transverse web connecting the ends of said body, an indicator pivotally mounted upon said web and having its outer end arranged adjacent the graduated face, tubular side members formed upon op-

posite sides of the indicator, a level tube arranged therein, and transverse resilient tongues disposed across the ends of the tubular side members to retain the level tube 15 therein.

In testimony whereof I hereunto affix my signature in the presence of two witnesses.

CHARLES G. SUTTON.
